UNITED STATES PATENT OFFICE.

WILLIAM H. STANSFIELD, OF AUBURN, NEW YORK.

DISPLAY-SUPPORTING DEVICE.

Application filed March 11, 1924. Serial No. 698,349.

This invention relates to devices for supporting articles for display purposes.

The invention relates more particularly to devices for supporting velocipedes for display purposes in stores and windows, although certain features thereof are not limited to use in the display of velocipedes but may be employed in supporting other articles.

10 One object of the present invention is to produce improved display supporting devices which will hold a velocipede or other article in a novel manner in a position to be readily inspected and examined, and so 15 that it presents a highly attractive appearance.

In supporting velocipedes for display purposes, it is desirable that the velocipede shall be supported so that all three wheels 20 are free to rotate. It is also desirable that the velocipede shall be so held that it may be removed readily from its support and placed on the floor. To produce supporting devices by which a velocipede may be held 25 in a manner to secure these results without the use of relatively complicated constructions which are conspicuous in appearance and mar the attractiveness of the display, has presented a difficult problem on account 30 of the peculiar construction of this article, more particularly on account of the construction of the frame.

Another object of the present invention is to produce display supporting devices for 35 velocipedes of simple construction and inconspicuous in appearance, by which these latter two results may be secured.

Different makes of velocipedes have different frame constructions, and another object of the invention is to provide supporting devices of simple construction which 40 will hold a velocipede with its wheels free, so that it may readily be removed from its support and which at the same time are 45 readily adaptable to different frame constructions.

With these and other objects in view, the invention comprises certain novel and improved constructions, arrangements, and 50 combination of parts hereinafter described,

and particularly pointed out in the claims, the advantages of which will be readily understood and appreciated by those skilled in the art.

The invention will be clearly understood 55 from the accompanying drawings, illustrating the devices embodying the invention in its preferred form and the following detailed description of the constructions there- 60 in shown.

In the drawings, Fig. 1 is a view in side elevation illustrating display supporting devices embodying the present invention;

Fig. 2 is a perspective view illustrating 65 certain parts of the support;

Fig. 3 is a detail sectional view taken substantially on the line 3—3, Fig. 2; and

Fig. 4 is a view in side elevation illustrating 70 a modification in the mode of operation of the supporting devices.

In the form of the invention illustrated in the drawings of this application, display supporting devices form part of a display rack similar to that disclosed in applicant's application, Serial No. 698,350 filed March 75 11, 1924.

This display rack comprises laterally extending supports 2 for the base of the rack, uprights 4, and crossbars 6 connecting the uprights to which laterally extending supporting arms 8 may be applied. The parts of this rack are preferably constructed of steel tubing having a rectangular cross-section and are connected together by suitable clamps to form a rigid structure. 80 85

The devices for engaging a velocipede to support the same may be attached either to the uprights 4 or to the crossbars 6, or if desired they may be mounted on the laterally extending arms 8 of the rack. In the construction shown, these devices are attached to one of the uprights 4. 90

The velocipede supporting devices comprise an arm 10, supported at its lower end upon one of the uprights 4 and arranged 95 to extend angularly in an upward direction from its point of support. Velocipedes of one well-known make, comprise a frame having a curved bar 12 forming the central portion or backbone of the frame, and an 100

inverted U-shaped portion 14 to which the rear end of the portion 12 is connected at substantially the central point of the U-shaped portion, the rear axle 16 being attached to the ends of the arms of the U-shaped portion. In the construction shown, the upper part of the arm 10 is recessed at 17 to receive the central part of the U-shaped portion of the frame of the velocipede, which is applied to the arm, as shown in Fig. 1. When the velocipede is engaged with the supporting arm 10 at this point on the frame, the weight of the forward part of the velocipede overbalances the rear part thereof and the forward part of the velocipede tends to swing downwardly about its point of engagement with the arm. In order to hold the velocipede substantially in the position shown in Figure 1 of the drawings, a stop bracket 18 is adjustably mounted on the arm 10, and is provided with lateral extensions 20 having at their ends angularly arranged flanges 22 for engagement with the axle 16 of the velocipede to limit the pivotal movement thereof.

To adapt the supporting devices for different sizes of velocipedes, a stop bracket 20 is mounted to slide longitudinally on the arm 10, and is held in adjusted position 25 on the arm by a set screw 24.

In another well-known type of velocipede, the portion of the frame between the seat and the rear axle is substantially Y-shaped, and there is no part of the frame which is adapted to seat in the recess 17 on the arm 10. To adapt the supporting devices for this type of velocipede frame, the arm 10 is provided with openings adjacent its upper end, through which may be inserted a rod 26, shown in dot and dash lines, Figure 2, for engagement beneath the branching sides of the Y-shaped part of the frame, as shown in Fig. 4.

The arm 10 is mounted on the element 45 of the display rack upon which it is supported, so that it may be adjusted longitudinally of this element. This enables the arm to be located in practically any desired position on the rack. In the illustrated construction the arm 10 is attached to a block 28 upon which are mounted clamping members 30 arranged to clamp the block to the upright 4. The construction of the clamping members is illustrated clearly in 50 Figure 3. The clamping members are attached to the block 28 by means of a bolt 32 passing through openings, respectively, in one of the clamping members and in the block 28, and threaded into the other clamping member. The clamping members are also provided with lateral flanges 34 arranged to engage the sides of the block 28, which prevent the clamping members from turning on the bolt 32 with relation to the block. The clamping members are arranged

to embrace the upright 4, as shown in Fig. 3, and are provided with lips 36 at their outer ends to overhang the side of the upright opposite the block 28. With this form of the clamp, the block 28 may be securely clamped in any desired position upon the upright 4. The members of the clamp are thus attached to the block 28 and may be readily released from clamping engagement with the upright 4 by unscrewing the bolt 32 partially from the clamping member into which it is threaded. The block 28 is preferably provided with two openings for the clamping bolt 32 at right angles to each other, so that the clamping jaws may 55 be applied to the sides of the block, as shown in the drawings, or may be applied to the top and bottom of the block. When the clamping members are applied to the top and bottom of the block, the block 28 is 60 adapted to be clamped either to the cross-bars 6 or to the laterally extending arms 8 of the rack.

In order to support different styles and sizes of velocipedes in a horizontal position, an angular adjustment of the arm 10 is required. To enable the arm to be angularly adjusted, the lower end of the arm is attached to a projection on the block 28 by means of a bolt 38, passing through the projection on the block and threaded into the lower end of the arm 10. When this bolt is loosened, the arm 10 may be adjusted about the bolt as a pivot, and may be secured in adjusted position by tightening the bolt. 65 The projection on the block 28 and the corresponding projection on the arm 10 are preferably provided with interengaging teeth to assist in holding the arm 10 securely in adjusted position.

In a modification of the type of velocipede shown in the drawing, a substantially straight portion of the frame extends from the central point of the U-shaped portion down to the rear axle parallel with the 70 arms of the U-shaped portion. The arm 10, as shown in Figure 2, is cut away on its lower side forming a slot or recess 40 in which this part of the frame between the arms of the U-shaped portion is received 75 when a velocipede of this construction is applied to the supporting arm.

It is to be understood that except as defined in the claims, the invention is not limited to the particular construction and arrangement of parts of the illustrated embodiment of the invention, but that the invention may be embodied in other forms within the scope of the claims.

What I claim as new and desire to secure by Letters Patent is:

1. Display supporting devices for velocipedes, comprising a support, an arm extending upwardly at an oblique angle from said support, means on said arm for engaging

- beneath the frame of a velocipede at a point between the rear axle and the seat, and stop means on said arm for engaging the velocipede at a point rearwardly of said first point 5 to limit the pivotal movement of the velocipede about said first point and thereby hold the velocipede in a substantially horizontal position with its wheels free to rotate.
2. Display supporting devices for velocipedes, comprising a support, and means extending from said support arranged to hold a velocipede solely through gravitational action with its wheels free, so that at all times it may be freely lifted from said support. 10
3. Display supporting devices for velocipedes comprising a support, and an arm extending from said support arranged to hold a velocipede solely through gravitational action with its wheels free so that at all times it may be freely lifted from said arm. 15
4. Display supporting devices for velocipedes comprising a support, an arm, means on said arm for engaging beneath the frame of a velocipede at a point between the rear 20 axle and the stop means for engaging a velocipede at another point to limit the pivotal movement of a velocipede about said first point, and thereby support the same in the desired position.
5. Display supporting devices for velocipedes, comprising a support, an arm extending from said support and arranged to engage beneath the frame of the velocipede at one point, and stop means mounted on said arm between the point of engagement with the frame and said support for engaging the velocipede at another point to limit the pivotal movement of the velocipede about the first point, and thereby support the same in the desired position. 25
6. Display devices for velocipedes comprising a support, an arm extending from said support and arranged to engage the frame of the velocipede at a point between the rear axle and the seat, and a device mounted on said arm for engagement with the rear axle to limit the pivotal movement of the velocipede about said first point, and thereby support the same in the desired position. 30
7. Display supporting devices for velocipedes, comprising a support, an arm extending from said support and arranged to engage beneath the frame at one point, and a bracket adjustable longitudinally of said arm for engaging the velocipede at another point to limit the pivotal movement of the velocipede about said first point, and thereby support the same in the desired position. 35
8. Display supporting devices for velocipedes comprising a support, an arm extending from said support and arranged to engage beneath the frame at a point between the seat and the rear axle, and a bracket adjustable longitudinally of said arm for en- 40
- gaging the rear axle to limit the pivotal movement of the velocipede about said first point, and thereby support the same in the desired position. 45
9. Display supporting devices for velocipedes comprising a support, an arm extending from said support and arranged to engage beneath the frame of the velocipede at one point, means carried by said arm for limiting the pivotal movement of the velocipede about said first point, and thereby support the velocipede in the desired position, and means at the end of said arm for securing said arm to said support, arranged to allow an angular adjustment of said arm in a vertical plane. 50
10. Velocipede display supporting devices comprising upright bars, crossbars connecting said upright bars, laterally extending supporting bars, means for supporting the upright bars in substantially vertical positions, and velocipede supporting devices secured to one of said bars and adjustable longitudinally thereof. 55
11. Velocipede display supporting devices, comprising upright bars, crossbars connecting said upright bars, laterally extending supporting bars, and velocipede display supporting devices mounted on one of said bars and adjustable angularly in a vertical direction. 60
12. Display supporting devices comprising side bars, crossbars connecting said side bars, devices for supporting a velocipede attached to one of said bars, and laterally extending base bars for supporting said side bars and crossbars. 65
13. Display supporting devices comprising a support, an arm extending from said support, means on said arm for engaging beneath an article to be supported at one point in the article so that the article is unbalanced with relation to this point of support, and means for engaging the article to be supported at a point above said article and in a part of the article which is overbalanced by another part thereof to limit the pivotal movement of the article about the first point. 70
14. Display supporting devices comprising a support, an arm extending from said support, means on said arm for engaging beneath an article to be supported at one point so that the article is unbalanced with relation to said point, and means for engaging the article to be supported at a point above said article and in a part of the article which tends to be lifted by the overbalancing weight of another part of the article to limit the pivotal movement of the article about the first point. 75
15. Display supporting devices comprising a support, means on said support for engaging beneath an article to be supported at one point therein so that the article is unbalanced, and means for engaging the article 80

to be supported at a point above said article and in a part of the article which tends to be lifted by the overbalancing weight of another part of the article to limit the pivotal movement of the article about the first point.

16. Display supporting devices for velocipedes comprising an arm, means on said arm

for supporting a velocipede at a point between the seat and the rear axle, and means to the rear of said first means for preventing a pivotal action about said point. 10

Signed at New York city, New York, this 3rd day of March, 1924.

WILLIAM H. STANSFIELD.
